PAINT SPRAY HOSE CLEANER OR THE LIKE

Donald J. Peeps, Toledo, Ohio, assignor to The De Vilbiss Company, Toledo, Ohio, a corporation of Ohio

Application August 3, 1948, Serial No. 147,915

Term of patent 14 years

(Cl. D49—1)

To all whom it may concern:

Be it known that I, Donald J. Peeps, a citizen of the United States, residing at 2602 Westbrook Drive, Toledo, in the county of Lucas and State of Ohio, have invented a new, original, and ornamental Design for a Paint Spray Hose Cleaner or the like, of which the following is a specification, reference being had to the accompanying drawing, forming part thereof.

In the drawing:

Fig. 1 is a front elevational view of a paint spray hose cleaner or the like showing my new design;

Fig. 2 is a top plan view thereof; and

Fig. 3 is a cross section taken on the line 3—3 of Figure 1.

I claim:

The ornamental design for a paint spray hose cleaner or the like, substantially as shown.

DONALD J. PEEPS.
